UNITED STATES PATENT OFFICE.

WILLIAM W. HOBE, OF NEW YORK, N. Y.

DESIGN FOR A BUTTON.

Application filed December 3, 1924. Serial No. 11,574. Term of patent 3½ years.

To all whom it may concern:

Be it known that WILLIAM W. HOBE, a citizen of the United States, and resident of the city of New York, in the county of New York and State of New York, has invented a new, original, and ornamental Design for Buttons, of which the following is a specification, reference being had to the accompanying drawing, forming part thereof, in which the figure is a perspective view of a button embodying my new design.

I claim:

The ornamental design for a button, as shown.

Dated New York city, November 29, 1924.
WILLIAM W. HOBE.
